UNITED STATES PATENT OFFICE.

FRANCIS H. RICHARDS, OF HARTFORD, CONNECTICUT.

COLLAPSIBLE TAP.

1,188,831.

Specification of Letters Patent. Patented June 27, 1916.

Application filed June 30, 1910, Serial No. 569,834. Renewed December 15, 1915. Serial No. 66,949.

To all whom it may concern:

Be it known that I, FRANCIS H. RICHARDS, a citizen of the United States, residing in Hartford, in the county of Hartford and 5 State of Connecticut, have invented certain new and useful Improvements in Collapsible Taps, of which the following is a specification.

The object of this invention is to provide 10 an improved construction of collapsible thread-cutting device, such as a tap or a die member, that will be strong and reliable in its operation, and can be quickly collapsed to withdraw it from the threaded article.

15 In the accompanying drawings representing one embodiment of my invention, Figure 1 is an end elevation with the chasers in the contracted position. Fig. 2 is a side elevation showing the chasers in contracted position. Fig. 3 is an end view similar to Fig. 1 showing the chasers in the expanded position. Fig. 4 is a section on the line 4—4 of Fig. 3 showing the chasers in open position. Fig. 5 is a side elevation similar to Fig. 2, 25 with the chasers in the open position. Fig. 6 is a section on the line 6—6, indicated in Fig. 4. Fig. 7 is a section on the line 7—7 indicated in Fig. 4. Fig. 8 is a rear view as seen on the line 8—8 in Fig. 4, with the rear 30 portion of the body member removed. Fig. 9 shows one of the slides. Fig. 10 shows the spindle for operating the slides; Figs. 11 and 12 show the two chaser members; and Fig. 13 shows the end view of the spindle.

35 The device is shown as comprising a shell or body member 1 of substantially rectangular form, having ways in it for guiding a pair of slide members 2 and 3 that are substantially identical; one of which is shown 40 separately in Fig. 9. This way is shown substantially in the form of a bore or slot 4. These slides are shown as each having an enlargement 5 at their intermediate portion that contains a channel 6 extending trans- 45 verse to the longitudinal axis of the slide.

The body member is shown as having an open portion 7 at the intermediate portion of the guideway 4, into which extend the enlargement 5 of the two slides, as best shown 50 in Fig. 4. The slides are arranged with the two slots 6 facing each other, and which at certain positions of the slides will register.

The thread-cutting members, that in the present construction comprise tap segments

or chasers, are shown as formed by two 55 members 8 and 9 that are substantially identical. Each comprises a cutter or chaser portion 10, and a shank portion 11. Each chamber member has a flat side 12 extending throughout the length, which faces 60 are brought together and on which they are brought together and on which they mutually slide in a path transverse to their longitudinal axis, as indicated in Figs. 1 and 3, showing the two different positions of the slides. Fig. 3 shows the chasers in 65 their expanded and operative position for engaging a bore to cut a thread therein, and Fig. 1 shows the chasers in their contracted or closed position, permitting them to be withdrawn from the tapped bore, out of engagement therewith and without requiring reverse rotation of the tap. The shank portions 11 of the tap are fitted into the slot portion 6 of the slides, and suitably secured 70 therein to extend transversely, or perpendicular to the axis of the slides. A bolt 13 passes through a bore 14 in each slide, and is screwed into a threaded hole 15 in each tap; whereby the chasers are rigidly secured 75 to the slides respectively. The body member 1 is provided with bores 16 and 17 through which the heads of the bolts 13 pass, and which bores are considerably 80 larger than the bolt heads to permit movement of the slides longitudinally in the body. 85 From this it will be seen that by moving the slides longitudinally or in the direction of their axis, the two chasers extending transversely therefrom will be given a movement 90 transverse to the axis of the chasers whereby they can be shifted to expand and to contract, as described with reference to Figs. 1 and 3. To insure parallel movement of the chasers, the chaser 8 is provided with a rib 18 fitting into a slot 19 in the chaser 9. 95 It will be seen from Figs. 4 and 5 that the cutter portion of the chaser members projects beyond the body member and can therefore enter into the bore of any article to cut a thread therein without interference with 100 the body member.

Means are carried by the body member for simultaneously reciprocating the slides to effect the contraction and expansion of the chasers. A spindle 20, shown separately in Fig. 10, is 105 mounted to turn in a bore 21 in the body member (see Fig. 4), and is provided with two pins 22 and 23 that engage slots 24 and

25 respectively in the slides 2 and 3. These pins are on opposite sides of the center of the spindle and consequently will cause the slides to be simultaneously shifted in opposite directions. A lever 26 is secured to the spindle and serves to cause the latter to shift the slides. It is the purpose of this lever to engage with any suitable member of the machine in which the device is employed, to 5 shift the chasers at the proper time. Means are also provided for retaining the chasers in the operative or expanded position, and that in the present device comprise an arm 27 connected with the lever 26, which arm 10 is engaged by a trip lever 28 pivoted on the body 1, and having a notched extremity 29 that will engage the arm 27 and hold the spindle, and with it the chasers, in the operative position. Resilient means are shown 15 tending to shift the lever and spindle to normally retain the chasers in the contracted or closed position, that will be operative as soon as the arm 27 is released from the trip lever 28. A spring plunger is shown comprising a plunger 30 slidable in a bore 31 in 20 the body, and pressed by a coil spring 32 against an abutment 33, formed by a notch in the spindle 20. The trip lever 28 is retained in engaging position by a coil spring 25 34; and has an arm 35 which at the proper time can be engaged by any suitable member on the machine to shift the trip lever against the force of this spring, causing the arm 27 to be released from the abutment of the trip 30 lever. Thereupon the spring plunger described will swing the spindle and cause the chasers to shift to the closed position. It will be understood that when the lever 26 is again swung, the arm 27 will slide against 35 the arm 28 of the trip lever causing the abutment 29 to engage the arm 27 when the lever 26 is released, and again engage the arm 27 to retain the parts with the chasers in the open or operative position.

40 Means are provided for adjusting the parts whereby the relative position of the chasers can be varied, when the arm 27 is engaged by the trip lever to hold the parts with the chasers in the open position. The arrangement shown for this purpose comprises screw bolts 37 and 38 carried by the lever 26 and engaging abutment faces 39 and 40 on opposite sides of the axis of the spindle 20, as shown in Figs. 8 and 10. 45 These bolts will serve to very nicely adjust the position of the lever 26 upon the spindle, and at the same time to securely lock the lever in the proper position.

If desired, a stop may be arranged on one 50 of the slides carrying the chasers to limit the relative movement of the slides. A pin 42 on the slide 2 is shown as projecting into an opening 43 on the slide 3 and in one direction of movement the pin will engage one 55 wall of this opening 43 and prevent further

movement. The relative movement in the opposite direction may be adjustably limited by means of a bolt 44 tapped into the slide 3 and projecting into the opening 43 to engage the pin 42.

In Fig. 1 the device is shown with the lever 26 engaged by a suitable stop 45 carried by some part of the machine on which the device is mounted, whereby the relative movement between the body member and this stop will cause the lever 26 to shift to the position indicated in the broken lines. This is indicated by the stop 45, being also shown in broken lines as having shifted relatively to the tapping device. But, of course, it will 80 be understood that the stop may be stationary on the machine and the tap shifted, as for instance the tap might be mounted on a turret and when advanced from its operative position the lever 26 will engage the stationary stop to shift the lever and thereby set the device.

The trip lever 35 will usually be engaged by a suitable stop member, as 46, that is movable relative to the tapping device in 90 the stationary or operative position of the latter and at the end of the cutting operation of the tap the stop or member 46 is advanced to engage the trip lever 35, causing it to release the arm 27 and permit the chasers to 95 be reset by the spring plunger.

It will, of course, be obvious that in practice it is indispensable that the two chasers 8 and 9 shall be maintained in accurate position longitudinally in order that the 100 threads thereon shall always conform to a true helical line, after the manner of the corresponding threads in the ordinary solid taps. The rib or spline 18 carried on one of said chasers and fitting into a slot, as 19, 105 in the other chaser constitutes a simple and effective means for preserving this alignment of the threads. It will also be observed that the manner in which the chasers are shifted after the purpose of "collapsing" 110 them to a smaller than normal diameter, is by sliding one of these chasers upon and against the other, and this in a direction transverse of the axis of the tap, so that no open spaces are formed either in opening or 115 closing the tap. By means of this construction the tool is prevented from gathering chips between the working faces of the movable parts thereon so that in practice it is found the tool can be employed continuously 120 without interference from the accumulation of dirt and chips upon or within the same.

In practice it is deemed desirable to accomplish the release of the retaining catch with a minimum, or relatively very slight 125 resistance to the forward movement of that portion of the machine (such for instance as the turret slide of a screw machine) by which the tool is carried. This object I attain by the long lever arm 38 combined with 130

- the actuators 22 and 23 having a relatively short radius of the faces which engage the tool-carrying slides 8 and 9. This arrangement operates to reduce the pressure on the 5 catch faces at 29, to such a small amount that it becomes feasible to employ a short arm, as 35, on which the tripping stop shall act for fully retracting the latch or catch during only a slight advance of the tool, so 10 that the required release is effected in the briefest possible period of time, thereby to secure an instantaneous and complete retraction of the cutting teeth, from the work as soon as there is any initial retraction 15 thereof. This important result is further accelerated or insured by the direct connection of the actuator and its rigidly-attached lever arm to the two tool-slides, thereby eliminating or avoiding the use of any intermediate members, and thus preventing the 20 accumulation of "play" due to wear or otherwise, and so eliminating the injurious results that frequently arise in practice from such accumulation.
- 25 A leading object of my present improvements is to furnish a tool especially adapted for use in screw-machines where the tools are deluged with large quantities of heavy oil carrying chips, oxids and dirt, and to 30 prevent these foreign and destructive materials from interrupting the operation of the tool mechanism through the gradual accumulation of the same in spaces between the working parts. This result I attain by 35 means of a peculiar organization of the working parts whereby "chip-spaces" are avoided, and whereby no non-contacting opposing and relatively parallel faces (of a partially exposed space) have a movement 40 toward and from each other.
- Such features of construction as are herein disclosed but are not herein claimed, the same being of my invention, are reserved to constitute in part the subject-matter of another application to be concurrently pending herewith; this reservation includes, especially, the construction of the cutting parts of the tap-blades as herein set forth in connection with Figs. 11 and 12.
- 50 Having thus described my invention, I claim:
1. A collapsible thread-cutting device comprising a body member having ways therein, a pair of slides movable in the ways, 55 a chaser carried by each of the slides and arranged together with their axes transverse to the slides to expand and contract upon reciprocation of the slides, a lever pivoted on the body member, means engaging each 60 slide with the lever to cause reciprocation of the slides in opposite directions on swinging the lever to open and close the chasers, a trip lever carried by the body and arranged to engage said lever to lock it securing the chasers in open position, and a

spring connected with the said former lever to swing it to cause the chasers to contract when released from the trip lever.

2. A collapsible thread-cutting device comprising a body member having ways 70 therein, a pair of slides movable in the ways, a chaser carried by each of the slides and arranged together with their axes transverse to the slides to expand and contract upon reciprocation of the slides, a lever pivoted 75 on the body member, means engaging each slide with the lever to cause reciprocation of the slides in opposite directions on swinging the lever to open and close the chasers, a trip lever carried by the body and arranged 80 to engage said lever to hold it securing the chasers in open position, a spring connected with the said former lever arranged to swing it to cause the chasers to contract when released from the trip lever, the trip lever 85 being arranged to reengage the operating lever when the latter is returned to shift the chasers to expanded position.

3. In a collapsible thread-cutting device, the combination of a body member having 90 a guideway, a pair of contiguous slides movable in said guideway, each slide having a channel on its engaging face oppositely located and extending transverse to the slide, a pair of similar chasers comprising a cutting portion and a shank alining therewith, the shank portions of the cutters respectively secured in the said channel portions of the guides with the chasers contiguous substantially throughout their length whereby 95 the reciprocation of the slides in opposite directions will cause the chasers to expand and contract their cutting areas, means for simultaneously reciprocating the slides in opposite directions, and means for locking the slides in the expanded position of the chasers.

4. In a collapsible thread-cutting device, the combination of a body member having a guideway, a pair of contiguous slides movable in said guideway, each slide having a channel on its engaging face oppositely located and extending transverse to the slide, a pair of similar chasers comprising a cutting portion and a shank alining therewith, 110 the shank portions of the cutters respectively secured in the said channel portions of the guides with the chasers contiguous substantially throughout their length whereby the reciprocation of the slides in opposite directions will cause the chasers to expand and contract their cutting areas, means for simultaneously reciprocating the slides in opposite directions, 115 means for locking the slides in the expanded position of the chasers, one chaser having a transverse slot, and a rib on the other chasers fitting said slot to guide the chasers.

5. In a collapsible thread-cutting device, the combination of a body member, a pair 120

of contiguous slides movable in said guideway, each slide having a channel on its engaging face oppositely located and extending transverse to the slide, a pair of similar chasers comprising a cutting portion and a shank alining therewith, the shank portions of the cutters respectively secured in the said channel portions of the guides with the chasers contiguous substantially throughout their length whereby the reciprocation of the slides in opposite directions will cause the chasers to expand and contract their cutting areas, means for simultaneously reciprocating the slides in opposite directions, means for locking the slides in the expanded position of the chasers, and guiding means between the chasers.

6. In a collapsible thread-cutting device, the combination of a body member, a pair of contiguous slides movable in said guideway, each slide having a channel on its engaging face oppositely located and extending transverse to the slide, a pair of similar chasers comprising a cutting portion and a shank alining therewith, the shank portions of the cutters respectively secured in the said channel portions of the guides with the chasers contiguous substantially throughout their length whereby the reciprocation of the slides in opposite directions will cause the chasers to expand and contract their cutting areas, means for simultaneously reciprocating the slides in opposite directions, means for locking the slides in the expanded position of the chasers, and a spring device carried by the body member for normally retaining the chasers in their contracted position.

7. In a collapsible thread-cutting device, the combination of a body member having a guideway, a pair of contiguous slides movable in said guideway, a pair of similar chasers secured in the said slides whereby the reciprocation of the slides in opposite directions will cause the chasers to expand and contract their cutting areas, a slide actuating spindle for simultaneously reciprocating the slides in opposite directions, a spindle carried by the body to swing, a pair of pins projecting from the spindle, the slides each having a notch engaged by one of the pins, a lever carried by the spindle, and means for adjusting the lever on the spindle, whereby to adjust the working of said slides and chasers.

8. In a collapsible thread-cutting device, the combination of a body member having a guideway, a pair of contiguous slides movable in said guideway, a pair of similar chasers secured in the said channel portions of the slides with the chasers contiguous whereby the reciprocation of the slides in opposite directions will cause the chasers to expand and contract their cutting areas, means for simultaneously reciprocating the

slides in opposite directions, comprised of a spindle carried by the body to swing and having an abutment portion, a pair of pins projecting from the spindle, the slides each having a notch engaged by one of the pins, an actuating lever carried by the spindle to cause the said reciprocation of the slides, and a spring plunger in the body engaging said abutment to normally cause the spindle to retain the chasers in closed position.

9. In a collapsible thread-cutting device, the combination of a body member having a guideway, a pair of contiguous slides movable in said guideway, each slide having a channel on its engaging face oppositely located and extending transverse to the slide, a pair of similar chasers comprising a cutting portion and a shank alining therewith, the shank portions of the cutters respectively secured in the said channel portions of the guides with the chasers contiguous substantially throughout their length whereby the reciprocation of the slides in opposite directions will cause the chasers to expand and contract their cutting areas and means for simultaneously reciprocating the slides in opposite directions, comprised of a spindle carried by the body to swing, a pair of pins projecting from the spindle, the slides each having a notch engaged by one of the pins, an actuating lever carried by the spindle to cause the said reciprocation of the slides.

10. In a collapsible thread-cutting device, the combination of a body member having a guideway, a pair of contiguous slides movable in said guideway, a pair of similar chasers secured in the slides whereby the reciprocation of the slides in opposite directions will cause the chasers to expand and contract their cutting areas, means for simultaneously reciprocating the slides in opposite directions, comprised of a spindle carried by the body to swing, a pair of pins projecting from the spindle, the slides each having a notch engaged by one of the pins, an actuating lever carried by the spindle to cause the said reciprocation of the slides, a latch bar pivoted on the body and having an abutment arranged to engage the lever to lock it in position to retain the chasers in the expanded position, a spring member in the body arranged to engage the spindle to swing it to shift the chasers to contracted position when the lever is released from the trip member, and a spring engaging the trip member causing it to engage said lever when the latter is swung to shift the chasers to expanded position.

11. In a collapsible thread-cutting device, the combination of a body member having a guideway, a pair of contiguous slides movable in said guideway, each slide having a channel on its engaging face oppositely located and extending transversely to the

- slide, a pair of similar chasers comprising a cutting portion and a shank alining therewith, the shank portions of the cutters respectively secured in the said channel portions of the guides with the chasers contiguous substantially throughout their length whereby the reciprocation of the slides in opposite directions will cause the chasers to expand and contract their cutting areas, 5 means for simultaneously reciprocating the slides in opposite directions, a spindle carried by the body to swing, a pair of pins projecting from the spindle, the slides each having a notch engaged by one of the pins, 10 a lever carried by the spindle to cause the latter to reciprocate the slides in opposite directions, a latch bar pivoted on the body and having an abutment arranged to engage the lever to lock it in position to retain the 15 chasers in the expanded position, a spring member in the body arranged to engage the spindle to swing it to shift the chasers to contracted position when the lever is released from the trip member, and a spring 20 engaging the trip member causing it to engage said lever when the latter is swung to shift the chasers to expanded position.
12. A collapsible thread cutting device comprising a body member having ways 25 therein, a pair of chaser-carrying members slidable in the ways to expand and contract the cutting portions of the chasers and having their contacting faces in a plane through the axis of the body-member, an actuator 30 engaging directly with both of said members to simultaneously open and close the chasers, an operating member connected with the actuator by means that are adjustable and arranged for varying the position of the 35 chasers for a given movement of the operating member by sliding the chasers on each other face to face, substantially as described.
13. A collapsible thread cutting device comprising a body member having ways 40 therein, a pair of chaser carrying members slidable in the ways to expand and contract chasers, an actuator engaging said members to simultaneously open and close the chasers, an operating member connected with the 45 actuator by means that are adjustable to vary the position of the chasers for a given movement of the operating member, actuator adjusting devices and a spring plunger carried by the body member engaging the 50 operating member to shift it to one limit of its movement and which is independent of the said adjustment means.
14. A collapsible thread cutting device comprising a body member having ways 55 therein, a pair of chaser members slidable in the ways to expand and contract their cutting portions, an actuator engaging said members to simultaneously open and close the chasers, an operating member, and connections between the actuator and the said 60 member comprising two abutment faces on one member and adjusting screws on the other member arranged to engage said faces to vary the position of the operating member relative to the actuator. 70
15. A collapsible thread cutting device comprising a body member having ways therein, a pair of chaser members slidable in the ways, a spindle mounted to turn in the body, connections between the spindle and chaser members to cause them to open and close when swung, a lever connected with the spindle to swing it, a trip lever having a fixed abutment engaged by said lever to hold the chasers in their cutting position, the said connection of the spindle and the lever being adjustable to vary the position of the chasers when the lever is engaged by the said abutment to hold the chasers in cutting position. 75
16. A collapsible thread cutting device comprising a body member having ways therein, a pair of chaser members slidable in the ways, a spindle mounted to turn in the body, connections between the spindle and chaser members to cause them to open and close when swung, a lever connected with the spindle to swing it, a trip lever having an abutment engaged by said lever to hold the chasers in their cutting position, the said connection of the spindle and the lever being adjustable to vary the position of the chasers when the lever is engaged by the said abutment to hold the chasers in cutting position. 80
17. In a collapsible thread cutting device, the combination of a body having a guideway, a pair of chaser members slidable in the guideway to open and close, actuating means including a lever for shifting the chasers, a trip lever having an abutment engaged by said lever to hold the chasers in cutting position, a spring connected with the operating lever arranged to hold it against said abutment of the trip lever and to swing the lever when the trip lever is shifted, and an adjustable stop member arranged to engage the operating lever when swung to re-engage the abutment face of the trip lever in order to prevent the lever moving too far when swung to engage the trip lever abutment face. 85
18. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 90
19. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 95
20. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 100
21. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 105
22. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 110
23. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 115
24. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 120
25. A collapsible thread cutting device comprising a body member having ways therein, a pair of elongated slides longitudinally movable in said ways with their opposed faces in engagement, each slide having a transverse channel in the engaging face at the intermediate portion, a pair of chasers comprising a cutter portion and a shank portion alining therewith, the shank portion of each chaser being secured in the 125

said channel portion of the slides respectively causing the chasers to extend transversely to the slides, the chasers having opposed faces in engagement substantially throughout their length and located in the plane of the engaging faces of the slides, and means for shifting the slides endwise to cause the chasers to shift transversely to their axis to open and close their cutter portions.

19. A collapsible thread cutting device comprising a body member having ways therein, a pair of slides longitudinally movable in the ways with their opposing faces in engagement substantially throughout their whole length, a pair of chasers each comprising a cutter portion and a shank portion, each chaser being secured to one of said slides, the chasers having engaging faces extending substantially throughout their length and parallel with the engaging faces of the respective slides, and means for shifting the slides endwise to cause relative movement of the chasers transverse to their axis, one of the chasers having a transverse guide slot in its engaging face, the other chaser having a rib fitting in the said slot to guide the chasers.

20. A collapsible thread cutting device comprising a body member having ways therein, a pair of slides longitudinally movable in the ways with their opposing faces in engagement substantially throughout their whole length, a pair of chasers each comprising a cutter portion and a shank portion, each chaser being secured to one of said slides, the chasers having engaging faces extending substantially throughout their length and parallel with the engaging faces of the respective slides, and means for shifting the slides endwise to cause relative movement of the chasers transverse to their axis, one of the chasers having a slot in its engaging face at the shank portion, the other chaser having a rib projecting from its shank portion into said slot in the other chaser to guide the chasers.

21. In a collapsible threading tool, the combination with a tap-blade carrier comprising two tap-blade-carrying members shiftable one relatively to the other laterally of the axis of the tool, and a single pair of tap-blades projecting forwardly of the carrier, one blade on each carrier respectively, and each blade having on the forwardly projecting part thereof thread-cutting teeth and having on the opposite edge thereof a curved face shiftable outwardly from the axis for guarding the teeth of the opposite blade when the tap is collapsed for withdrawal from a threaded hole, said blades and the carriers therefor being arranged in face to face contact in one plane which is an axial plane of the tool.

22. In a collapsible threading tool, the

combination with a tap-blades carrier comprising two tap-blade carrier-slides shiftable one relatively to the other laterally of the axis of the tool, and two tap-blades projecting forwardly of the carrier one blade on each carrier-slide respectively, and each blade having on the forwardly projecting part thereof thread-cutting teeth and having on the opposite edge thereof a curved face shiftable outwardly from the axis for guarding the teeth of the opposite blade when the tap is collapsed for withdrawal from a threaded hole, said blades and the carriers therefor being arranged in face to face contact in an axial plane of the tool.

23. In an adjustable collapsing tap, in combination, a pair of tap-blade carriers having each a tap-blade seat, and located and movable face to face in contact in an axial plane of the tap, and arranged for holding a pair of tap-blades in axial alignment and disposed longitudinally thereof; a pair of tap-blades arranged face to face and longitudinally of said axis, fastening means arranged for removably securing the blades in said carrier blade-seats, and arranged for the blades to be withdrawn from said seats longitudinally of the axis, and operating and stroke-adjusting means for said carriers arranged for shifting one carrier relatively to the other transversely of said axis, whereby the centrally-located tap-blades and the carriers meet and move with their contacting faces in one and the same central working plane.

24. In an adjustable collapsing tap, in combination, a pair of tap-blade carriers having each a tap-blade seat, and located and movable face to face in contact in an axial plane of the tap, and arranged for holding a pair of tap-blades in axial alignment and disposed longitudinally thereof; a pair of tap-blades arranged face to face and longitudinally of said axis, fastening means arranged for removably securing the blades in said carrier blade-seats, and arranged for the blades to be withdrawn from said seats longitudinally of the axis, operating and stroke-adjusting means for said carriers arranged for shifting one carrier relatively to the other transversely of said axis, and pitch-alining guide-faces between the blades and arranged in position for preventing longitudinal movement of one blade relatively to the other while permitting the transverse movement of the blades with their respective carriers.

25. In an adjustable collapsing tap, in combination, a pair of tap-blade carriers having each a tap-blade seat, and located and movable face to face in contact in an axial plane of the tap, and arranged for holding a pair of tap-blades in axial alignment and disposed longitudinally thereof; a pair of tap-blades arranged face to face

and longitudinally of said axis, fastening means arranged for removably securing the blades in said carrier blade-seats, and arranged for the blades to be withdrawn from said seats longitudinally of the axis, operating and stroke-adjusting means for said carriers arranged for shifting one carrier relatively to the other transversely of said axis, and pitch-aligning means operative be-

tween the blades for preventing longitudinal movement of one blade relatively to the other while permitting the transverse movement of the blades relatively to each other.
